UNITED STATES PATENT OFFICE.

LEWIS P. HALLADAY, OF STREATOR, ILLINOIS.

PHONOGRAPH-HORN SUPPORT.

No. 836,031.

Specification of Letters Patent.

Patented Nov. 13, 1906.

Application filed September 21, 1905. Serial No. 279,400.

To all whom it may concern:

Be it known that I, LEWIS P. HALLADAY, a citizen of the United States, residing at Streator, in the county of Lasalle and State 5 of Illinois, have invented a certain new and useful Improvement in Phonograph-Horn Supports, of which the following is a specification.

My invention relates to supporting devices 10 for phonographs and the like, and has for its object to provide means for supporting the horn of a phonograph which shall be adjustable, permit the movement of the horn incident to the travel of the reproducer, and will 15 be collapsible for convenience in transportation.

The invention is illustrated in the accompanying drawings, wherein—

Figure 1 is a side elevation of a phonograph 20 and horn with my supporting device in operative position; Fig. 2, a detail end elevation of the horn-carrying members; Fig. 3, a side view of the supporting-pin on the phonograph-case, and Figs. 4 and 5 views of the device 25 taken apart and collapsed for packing.

Like letters of reference indicate like parts in all the drawings.

I have shown and shall describe my invention as used for supporting the outer end of a 30 phonograph-horn adapted to travel with the reproducer of a phonograph in the customary manner; but it will be evident that the device is capable of use in other connections where similar conditions are met with.

35 In the drawings, A represents the phonograph-casing, B the mandrel, carrying the record B', and C the moving reproducing mechanism, generally speaking, carrying the horn D, preferably connected therewith by 40 the flexible tube D'.

The horn-supporting device which forms the subject-matter of this application consists in general of a horizontal part supported by and braced against the phonograph-case, as will be described, and an upright part, from which the horn is hung, the two parts of the device being preferably separable.

45 The horizontal member of the device consists of a tube E, fitting over a pin E' on a plate E², secured to the front of the phonograph-case in any desired manner, said pin being preferably notched or cut away at E³ to form a seat for the locking thumb-screw E⁴, 50 which passes through a collar E⁵ on the tube E. The collar E⁵ is extended below the tube

E to form a yoke E⁶, to which is pivoted the diagonal brace E⁷, to the end of which is pivoted a horizontal brace E⁸, having near its extremity the loop or other projection E⁹ 60 and beyond the same an extension E¹⁰, adapted to take under the edge of the phonograph-casing. The part E⁸ may be formed of a flattened strip of material twisted at E¹¹, so as to bring its flat side along the table upon 65 which the phonograph-casing rests. The diagonal brace E¹², pivoted to the part E⁷, is pivoted at its other end to a yoke on a sliding collar F¹³, which may be fixed at the proper place on the tube E by means of a set- 70 screw F¹⁴.

Sliding in the end of the tube E is a rod F, which may be extended to any desired length, according to the length of the horn supported, and it is held in place by means of 75 a set-screw F', the rod being preferably flattened at F², so as to give a bearing for the set-screw. The rod F is perforated near its outer end to receive a vertical rod G to be set in said perforation by means of the set- 80 screw G'. The upper end of the rod G has rigid therewith the yoke G², in which is pivoted an arm H, which is set diagonally to accommodate the horn and carries pivoted thereto an arm H', having a chain H² with a 85 hook H³, which hooks into a ring H⁴ on the horn. In order to keep the arms H H' at their proper angles, I provide at the joint a yoke H⁵, which acts as a stop, and a similar part H⁶, pivoted to the lower end of the arm 90 H, catches over a shoulder H⁷ on the yoke G², so as to prevent the arm H from being moved inwardly at its joint with the yoke.

Figs. 4 and 5 show the horizontal and the upright parts, respectively, of the device 95 separated and separately collapsed and folded up ready for packing.

The use and operation of my device will perhaps have been made sufficiently clear by the foregoing. It will be evident that the 100 horizontal portion of the device as it is adapted for use in the connection shown may be extended or collapsed, so as to accommodate the device for different sizes of horns and that the pitch of the horn may be 105 changed by vertical adjustment of the rod G. The arrangement of the braces E⁷, E⁸, and E¹² is, in effect, the widening of the base of the casing A on the table and affords very 110 efficient means for bracing the horizontal member of the horn-support, so that a heavy large horn may be used without danger of

overbalancing the phonograph. A heavy horn will overbalance a relatively small and light phonograph-box unless this tendency so to do be overcome. This tendency can be 5 overcome by an extension of the base of the phonograph-box outwardly in the direction of the horn. To provide such an extension and make it capable of folding and remaining attached to or integral with the horn-support is a desirable object accomplished by 10 my invention. The piece E³ may be called a "base" extension for the phonograph-box. Such an extension can be foldingly connected with the horn-support proper or tube E in any desired manner—for example, by 15 the two pivoted braces shown. The tube E and its associated parts may be looked upon as the body of the support.

I claim—

- 20 1. In a supporting device for phonograph-horns and the like, the combination of a substantially horizontal member with a fixed bearing part upon the phonograph apparatus with which such horizontal member is removably connected, and a supporting structure for such member comprising a brace below such horizontal member and abutting against the phonograph-case, and pivoted connections connecting the brace with such horizontal member.
- 25 2. In a supporting device for phonograph-horns and the like, the combination of a substantially horizontal member with a fixed bearing part upon the phonograph apparatus with which such horizontal member is removably connected, and a supporting structure for such member comprising a brace below such horizontal member and abutting against the phonograph-case, a link connecting the brace with thinner end of such horizontal member, and another link connecting such link with the horizontal member.
- 30 3. In a supporting device for phonograph-horns and the like, the combination of a substantially horizontal member, with means for securing the same to the phonograph apparatus, a horn-supporting frame comprising angularly-disposed arms one above the other and from the upper of which said horn is hung, means for pivotally supporting said framework at the outer end of the horizontal member, and a locking device to hold said pivoted framework in its upright position.
- 35 4. In a supporting device for phonograph-horns and the like, the combination of a substantially horizontal member, with means for securing the same to the phonograph apparatus, an upright member connected with the horizontal member comprising a rod and two angularly-placed arms one above the other, the lower arm being pivotally attached to the rod, means for supporting the horn from the upper of said arms, and a locking device to hold the lower arm in fixed relation with the 40 rod.

5. A supporting device for phonograph-horns and the like comprising a substantially vertical part, a pair of diagonally-disposed arms pivoted one above the other and pivoted to the vertical part, means for hanging the 70 horn from the upper of said arms, and a clip on the lower of said arms engaging with the vertical part to lock said arm in its operative position.

6. In a supporting device for phonograph-horns and the like, the combination of a base extension-piece for the phonograph-box with a horn-supporting body attached to the front of the box above the extension-piece and connections between the two whereby they are 80 foldingly secured together.

7. In a supporting device for phonograph-horns and the like, the combination of a base extension-piece for the phonograph-box with a horn-supporting body attached to the front 85 of the box above the extension-piece and pivotally-joined connections between the two whereby they are foldingly secured together.

8. In a supporting device for phonograph-horns and the like, the combination of a base 90 extension-piece for the phonograph-box with a horn-supporting body attached to the front of the box above the extension-piece and two pivotally-joined connecting-bars between the two so as to permit them to fold together. 95

9. In a supporting device for phonograph-horns and the like, the combination of a horn-holding structure attached to the front of the phonograph-case, with a bracing structure below the same and having a bearing in front 100 of the phonograph-case, and a connection from the holding structure to the bracing structure transmitting the weight of the horn from the former to the latter.

10. In a supporting device for phonograph-horns and the like, the combination of a horn-holding structure attached to the front of the phonograph-case, with a bracing structure below the same and having a bearing in front 110 of the phonograph-case and a bearing against said case, and a connection from the holding structure to the bracing structure transmitting the weight of the horn from the former to the latter.

11. In a supporting device for phonograph-horns and the like, the combination of a horn-holding structure attached to the front of the phonograph-case, with a bracing structure below the same and having a bearing in front 115 of the phonograph-case, and a connection from the holding structure to a point on the bracing structure forward of the case transmitting the weight of the horn from the holding structure to the bracing structure.

12. In a supporting device for phonograph-horns and the like, the combination of a horn-holding structure attached to the front of the phonograph-case, with a bracing structure comprising a horizontal member lying along 120 the surface on which the case rests in front of 130

said case, and a connection from the holding structure to the bracing structure transmitting the weight of the horn from the former to the latter.

5 13. In a supporting device for phonograph-horns and the like, the combination of a horn-holding structure attached to the front of the phonograph-case, with a bracing structure comprising a horizontal member lying along 10 the surface on which the case rests in front of said case, an oblique member extending from the outer end of said horizontal member to the front of the case, and a connection from the holding structure to said oblique member.

14. In a supporting device for phonograph-horns and the like, the combination of an extensible rod attached to the front of the case, with a horizontal member lying along the surface upon which the case rests and having a part bearing against the case, a link connecting the outer end of the horizontal structure with the inner end of the extensible rod, and a link connecting the aforementioned link with said extensible rod. 15 20
